REPEATER

Application filed January 4, 1930, Serial No. 418,444, and in Germany April 17, 1929.

The invention relates to a circuit arrangement for transmitting current impulses by induction over connecting lines in communication systems, especially to those in which direct current is used for generating the current impulses.

It is known to generate induced impulses in the secondary winding of the repeater by opening and closing a direct current circuit extending over the primary winding of the repeater at the outgoing end of the connecting line or by strengthening and weakening the direct current in this circuit. But in these systems, especially in those having long lines, difficulties arise, because the impulses are much damped owing to the inductive and capacity resistances of the lines and they are therefore so weakened that they do not suffice to reliably operate the switching means to be influenced at the incoming end of the connecting line.

These difficulties are overcome by the invention and thus a greater range of the impulses is obtained. This is achieved in that at the outgoing end of the connecting line the direct current circuits extending over the primary winding of the repeater used for transmitting the current impulses are so opened and closed at every impulse to be transmitted, that the induced impulse generated in the secondary winding by opening the one circuit is lengthened by that generated by closing the other circuit.

In the Figs. 1 and 2 are shown two methods of carrying out the invention by way of example. In the arrangement shown in the Fig. 1, the lengthened impulses of current are sent in alternate direction over the connecting leads V_b 1 and V_b 2; while in the arrangement shown in the Fig. 2 they are always sent in the same direction over the connecting leads V_b 3 and V_b 4.

The arrangement according to Fig. 1 operates in the following manner: The change-over contacts 1 α 1 and 2 α 1 oscillate when the relay A 1 is alternately energized and deenergized owing to the interruption of its circuit in known manner, for instance by a number dial. Each time the relay A 1 is operated, the contacts 1 α 1 and 2 α 1 are opened and the

contacts 3 α 1 and 4 α 1 are closed. The opening as well as the closing of the contacts causes a change in the current in the primary winding of the repeater and thus creates an induced impulse in the secondary winding. 55 The contact changes succeed one another so quickly that the induced impulse generated by the opening of the contacts has not died down when that generated by the closing of the contacts starts and in the generating circuit the current reversal associated with the change-over of the contacts causes the two induced currents in the secondary winding to flow in the same direction as explained hereafter. The result of this is that the second 60 induced impulse assists the first, so that each time the relay A 1 is energized, a lengthened current impulse of particular direction passes over the junction leads V_b 1 and V_b 2.

The process is repeated each time the relay 70 A 1 is released, so that the pair of current impulses due to the opening of the contacts 3 α 1 and 4 α 1 and the closing of the contacts 1 α 1 and 2 α 1 are combined to form a single lengthened impulse of current, which however flows over the connecting leads V_b 1 and 75 V_b 2 in a direction, which is opposite to that of the induced impulse generated in the secondary winding of the repeater when the relay A 1 is energized.

Fig. 2 shows another method of carrying out the invention. This arrangement causes all the impulses transmitted over the junction leads V_b 3 and V_b 4 to flow in the same direction. 85

This arrangement functions in the following manner: Current normally flows over the following circuit when the arrangement is ready for operating: battery, resistance W 2, contact 1 α 2, primary winding of the repeater U_e 2 contact 2 α 2, relay S, battery. Relay S is energized in this circuit and has opened its contact 11 α , which takes up position 10 α .

When as above described the relay A 2 is 90 energized and released in known manner, its change-over contacts 1 α 2 and 2 α 2 are operated. The above described normally closed circuit is opened at contacts 1 α 2 and 2 α 2. This opening of the direct current circuit 100

effects a change in the current in the primary winding of the repeater and so induces a current in its secondary winding.

At the same time relay S falls back and closes its contact $11\ s$, thereby preparing a locking circuit for relay R . When relay $A\ 2$ has operated and has closed contacts $3\ a\ 2$ and $4\ a\ 2$, a direct current circuit is closed from battery over resistance $W\ 2$, contact

$10\ 4\ a\ 2$, primary winding of repeater $Ue\ 2$, contact $3\ a\ 2$, winding I of relay R to battery.

The closing of this circuit again effects a change in the current in the primary winding of the repeater and so induces an impulse in its secondary winding. The direction of this induced current will now be explained.

When a current flowing in a circuit a is interrupted, the opening of this circuit creates an induced current in an adjacent conductor b and its direction is determined by the direction of the current in the circuit a . When this circuit is closed again, an induced impulse is created in the adjacent conductor b , the direction of which is opposite that of the current induced in conductor b due to the opening of the circuit a . Therefore the direction of the induced current depends on the direction of the created current and changes with the opening and closing of the circuit creating it, provided that the direction of the current remains constant.

But in the present example when the relay $A\ 2$ is energized, its contacts do not open and close the same circuit. In addition, when one circuit is opened and the other circuit is closed, a reversal of current takes place at the same time, hence the creating current flowing over the primary winding of the repeater $Ue\ 2$ before the one circuit is opened flows in the opposite direction to the other creating current flowing over the primary winding due to the closing of the other circuit. Owing to the fact that, as already mentioned, the induced current, which is due to the opening and closing of the creating current that flows in the same direction, changes its direction, it follows that conversely if the creating current changes its direction, the induced current retains its direction.

Therefore the induced current created by the closing of the contacts $3\ a\ 2$ and $4\ a\ 2$ flows in the same direction over the secondary winding of the repeater as the induced impulse in this winding due to the opening of the contacts $1\ a\ 2$ and $2\ a\ 2$; and the induced current flows over the contact $5\ r$, the connecting lead $Vb\ 3$, back over the connecting lead $Vb\ 4$ and the contact $6\ r$.

As in the previously described example, here also the induced impulse created by the closing of the contacts $3\ a\ 2$ and $4\ a\ 2$ follows so quickly the one created by the opening of the contacts $1\ a\ 2$ and $2\ a\ 2$ —this being due to the short time elapsing between the contact change-over—that the two currents fol-

low each other so quickly that only a single prolonged current impulse reaches the connecting leads. Thereupon the relay R is operated by its winding I and switches over the contacts $5\ r$ and $6\ r$ into the position $7\ r$ ⁷⁰ and $8\ r$, and at its contact $9\ r$ it closes a locking circuit for itself over: earth, contacts $9\ r$, $11\ s$, winding II of relay R , battery, earth.

If the relay $A\ 2$ now falls back, the contacts $3\ a\ 2$ and $4\ a\ 2$ are opened again and the contacts $1\ a\ 2$ and $2\ a\ 2$ are closed. This opening again causes a current alternation in the primary winding of the repeater $Ue\ 2$ and thereby an induced impulse in its secondary winding. Similarly the closing of the contacts $1\ a\ 2$ and $2\ a\ 2$ causes an induced impulse to be created in the secondary winding of the repeater. The direction of both impulses is the same, but opposite to the direction of the current impulse, which reached the connecting line over the contacts $5\ r$ and $6\ r$, because the creating current, which is interrupted by the opening of the contacts $3\ a\ 2$ and $4\ a\ 2$ when the relay $A\ 2$ falls back,

⁸⁰ flows in the opposite direction to that of the creating current, which is interrupted by the opening of the contacts $1\ a\ 2$ and $2\ a\ 2$ when the relay $A\ 2$ is energized. The prolonged induced impulse, which is due to the relay ⁹⁰ $A\ 2$ falling back and therefore flows in the direction opposite to that of the impulse due to the relay $A\ 2$ pulling up, does not, however, reach the connecting line in this opposite direction, because while the contacts changed over from $3\ a\ 2$ to $1\ a\ 2$ and from $4\ a\ 2$ to $2\ a\ 2$, the contacts $7\ r$ and $8\ r$ are closed, as the relay S does not operate again until the contacts $1\ a\ 2$ and $2\ a\ 2$ are closed, and it then at its contact $11\ s$ interrupts the locking circuit of the relay R .

When this has been effected, the relay R falls back and the contacts $7\ r$ and $8\ r$ are opened and contacts $5\ r$ and $6\ r$ are closed; hence when the relay $A\ 2$ is again operated, the cycle can be repeated again.

Therefore by means of this arrangement it is achieved that the induced impulses, which are created by the energizing and de-energizing of the impulse receiving relay, are not only lengthened, but also pass over the connecting line in the same direction.

What is claimed is:

1. In a telephone system, a line and a trunk coupled by a repeating coil, an impulse receiving relay connected to said line, two direct current circuits each including the primary winding of said repeating coil, and contacts on said impulse receiving relay for opening one circuit and closing the other at each energization or deenergization of said relay whereby the impulse induced in the secondary winding of said coil due to the opening of one circuit is lengthened by the ¹²⁰ ¹²⁵ ¹³⁰

impulse induced in the secondary winding due to the closing of the other circuit.

2. In a telephone system, an impulse repeater including a repeating coil, two direct current circuits each including the primary winding of said coil, a trunk line connected to the secondary winding of said coil, and means for reversing the current through said primary winding by opening one of said circuits and closing the other whereby a single impulse is transmitted over said trunk line, said impulse consisting of the induced current generated by the opening of one circuit and the induced current generated by the closing of the other circuit.

3. In an impulse repeater, a repeating coil, two direct current circuits each including the primary winding of said coil, a trunk line connected to the secondary winding of said coil, means for opening one of said circuits and closing the other thereby reversing the current through said primary winding and inducing an impulse of current in said secondary winding, and means for reversing the trunk connections to said secondary winding at the end of each impulse so that all impulses are transmitted in the same direction over said trunk line.

4. In an impulse repeater, a repeating coil, a trunk line connected to the secondary winding of said coil, means for reversing the current through the primary winding of said coil thereby inducing a single impulse in said secondary winding, and means responsive to said first means for reversing the trunk connections to said secondary winding at the end of each impulse so that all impulses are transmitted over said trunk line in the same direction.

5. In a telephone system, a line and a trunk connected by a repeating coil, a battery connected to the primary winding of said coil, and means responsive to impulses received over said line for reversing the connections of said battery to said primary winding whereby impulses are induced in said secondary winding, each induced impulse consisting of the induced currents due to the opening of the battery connections and the closing of the reversed connections.

6. In an impulse repeater, a repeating coil, two direct current circuits each including the primary winding of said coil, a trunk line connected to the secondary winding of said coil, means for opening one of said circuits and closing the other thereby reversing the current through said primary winding and inducing an impulse of current in said secondary winding, a relay, means for operating said relay and locking it energized when one of said circuits is closed, means for opening the locking circuit of said relay and allowing it to release when the other circuit is closed, and contacts on said relay for re-

versing the connections of said trunk line to said secondary winding.

In witness whereof, I hereunto subscribe my name this 2nd day of December, A. D. 1929.

FRITZ LUBBERGER.
